Edward L. Brooks.*

UNITED STATES PATENT OFFICE.

GARRITT H. OLIVER AND EDWARD L. BROOKS, OF CHICAGO, ILLINOIS,
ASSIGNORS OF ONE-FOURTH TO ROBERT S. HOBBS, OF BROOKLYN,
NEW YORK.

BOTTLE-STOPPER.

SPECIFICATION forming part of Letters Patent No. 429,579, dated June 3, 1890.

Application filed March 17, 1890. Serial No. 344,427. (No model.)

To all whom it may concern:

Be it known that we, GARRITT H. OLIVER and EDWARD L. BROOKS, citizens of the United States, residing at Chicago, in the county of Cook and State of Illinois, have jointly invented certain new and useful Improvements in Self-Adjusting Bottle-Stoppers; and we do hereby declare the following to be a full, clear, and exact description of the same, reference being had to the accompanying drawings, forming a part of this specification, and in which—

Figure 1 is a vertical axial section of a stopper embodying our present improvements, the parts being shown in their normal expanded condition; Fig. 2, a side elevation, partly sectionized, of the same in a diametrically-contracted condition, showing a slightly-modified arrangement of the circular stiffening-rings of the present improvement; Fig. 3, a similar view illustrating another modified form of our present improvement.

Similar letters of reference indicate like parts in the several views.

The present invention relates to that form of self-adjusting bottle-stoppers in which a seamless elastic bulb or bag is adapted to expand within the mouth of the bottle, the adjustment of the bulb being attained by its own elasticity, while its adjustment is effected by a longitudinally-moving plunger within the bulb, which on being pressed down elongates the bulb and decreases the diameter to fit the required size of bottle-neck, and when released allows the bulb to expand to form a tight and effective closure of the bottle-neck. Such stoppers as formerly constructed were defective in the one point—to wit, the liability of the comparatively thin and very flexible material composing the elastic bulb-wall to fold or crease upon itself and form longitudinal grooves or channels in the sides of the bulb or bag, through which the gases and liquids contained in the bottle would leak and escape. This very serious defect we avoid in our present invention by the provision of one or more circumferen-

tially-arranged rings or enlargements *a*, of some thickness and rigidity, integral with the body of the bulb *A*, as shown, the action 50 of which is to circularly stiffen the walls of the bulb and prevent the same from becoming creased or folded as it expands into a narrow-necked bottle. The rings or enlargements *a* may be arranged on the interior of 55 the bulb, as indicated in Fig. 1, or partly on the interior and partly on the exterior of the bulb, as indicated in Fig. 2, or wholly on the exterior, as indicated in Fig. 3, without departing from the spirit of this part of our invention.

The second part of our present improvement consists in the employment of a cap *B*, of metal or other suitable material, for more effectively attaching the mouth of the elastic 65 bulb *A* to the rigid guide-core *C* at the mouth of the bulb, that forms a guide for the longitudinally-moving plunger *D*, the cap being secured in place by being pressed in against the bulb-neck immediately beneath 70 the lower rim of the core-piece, as shown, and in addition to forming a means of attachment for the parts said cap also acts to protect and shield the top of the bulb from damage, &c.

We are aware that prior to our invention expanding bottle-stoppers have been constructed with heavy thick walls upon which were formed a circumferential bead or beads to decrease the superficial area of the body 80 of the stopper in forming a joint or closure in the bottle-neck. We therefore do not claim any such arrangement or combination, broadly; but

What we do claim as our invention, and desire to secure by Letters Patent, is—

1. A self-adjusting bottle-stopper comprising, in combination, an elastic bulb *A*, formed of a thin flexible material and provided with circumferential stiffening-rings in its expanding body portion, a guide-core *C*, and a longitudinally-moving plunger *D*, essentially as herein set forth.

2. A self-adjusting bottle-stopper compris-

ing, in combination, an elastic bulb A, a core C in the mouth of the same, a cap B, the lower edge of which is pressed in against the bulb-neck immediately beneath the lower rim of 5 the core-piece to secure the bulb to the core, and a longitudinally-moving plunger D, essentially as herein set forth.

In testimony whereof witness our hands this 14th day of March, 1890.

GARRIT H. OLIVER.
EDWARD L. BROOKS.

In presence of—

ROBERT BURNS,
PETER P. DYER.
